UNITED STATES PATENT OFFICE.

MELVIN BARBER, OF OKLAHOMA, OKLAHOMA TERRITORY.

TOOL-HOLDER.

No. 800,258.

Specification of Letters Patent.

Patented Sept. 26, 1905.

Application filed December 28, 1903. Serial No. 186,860.

To all whom it may concern:

Be it known that I, MELVIN BARBER, a citizen of the United States, residing at Oklahoma, in the county of Oklahoma and Territory of Oklahoma, have invented a new and useful Tool-Holder, of which the following is a specification.

The present invention relates to a novel tool-holder, which may be employed for various purposes—as, for instance, a bit-stock; and the object is to provide an article of this character embodying a rotary shell constructed for easy manipulation to operate gripping jaws that will retain the shank of a bit firmly within the stock or permit the release therefrom when the shell or sleeve is rotated in opposite directions.

A further object of the invention is to obtain the positive actuation of the jaws in both directions, thus eliminating the necessity of springs either for the actuation or retention of any element which may be co-operatively related to the jaws.

A still further object is to provide novel means for holding the elements in their co-acting relation, said means also constituting a brake or friction device for preventing a too free movement of the shell.

The preferred embodiment of the invention is illustrated in the accompanying drawings, though various changes may be made from the construction set forth without departing from the spirit of the invention.

In said drawings, Figure 1 is a side elevation of the improved holder. Fig. 2 is a longitudinal sectional view through the same. Fig. 3 is a view similar to Fig. 2, the section being taken in a plane at right angles to that of said figure. Fig. 4 is a longitudinal sectional view of the shell or sleeve detached. Fig. 5 is a detail perspective view of the head and jaws removed from the shell or sleeve. Fig. 6 is a cross-section taken on the line 6 6 of Fig. 2, but showing the pivots in elevation. Fig. 7 is a cross-sectional view taken on the line 7 7 of Fig. 2. Fig. 8 is an end elevation of the sleeve. Fig. 9 is an end view of the complete holder.

Similar reference-numerals indicate corresponding parts in all the figures of the drawings.

In the embodiment illustrated a suitable shaft or spindle 10 is employed, which may constitute a part of a brace or other actuator, said spindle having an enlarged head 11 at one end, which is bifurcated by the provision

of a longitudinally-disposed slot 12, extending from the free end of the head to a point contiguous its opposite end. This slot preferably has its intermediate portion enlarged, 60 as shown at 13. The slot constitutes a seat for a pair of clamping or gripping jaws 14, having pivots 15 located between their ends and detachably fitted in notches or sockets 16, located on opposite sides of the slot 12. 65 The ends of the jaws are enlarged, as shown at 17 and 18, so that they will project beyond the side faces of the head. The ends 18 are provided with outstanding lugs 19, and the corresponding end of the head 11 also has peripheral outstanding flanges 20, the portions 19 of the jaws fitting between and corresponding in shape to said flanges. The adjacent or opposing inner faces of the jaws are preferably angular in cross-section, as shown at 21, 70 and are designed to receive and firmly engage the squared stem 22 of a tool-shank 23. The portions 17 of the jaws in rear of the pivots 15 may be termed "tailpieces."

From the above construction it will be seen 80 that when the tailpieces are forced within the plane of the periphery of the head the jaws proper will move outwardly beyond the periphery of the head, and vice versa. It therefore follows that if positive means are provided for alternately urging the tailpieces and the jaws proper toward the axis of the shank positive actuation of the jaws will be secured in both directions, the depression or inward movement of the tailpieces serving to separate 90 the gripping-faces 21 and similar movement of the jaw portions 18 serving, of course, to bring said faces into clamping contact with the shank of the bit or other tool to be held. For the purpose of accomplishing 95 these movements a rotary sleeve or shell 24 is employed which incloses the jaws and the head, with the exception of the outstanding portions 19 and the flanges 20, against which the sleeve is arranged to abut. This sleeve 100 is provided with oppositely-disposed pairs of cam-ribs 25 and 26, one pair of which is opposed to the jaw portions proper, 18, while the others, 26, coact with the tailpieces 17. Obviously the jaw portions and tailpieces 105 must be arranged for alternate actuation, and provision must be made for permitting one end to move in a direction opposite to the direction in which the other is urged under the impulse of the rib. Said ribs are therefore 110 disposed in alternating arrangement—that is to say, the ribs 25 are disposed in diametric-

ally-opposed relation, and the ribs 26, while being relatively disposed in a similar manner, are located in planes intermediate of the ribs 25. In other words, they are disposed at the 5 opposite ends of a diameter bearing a right-angular relation to that upon which the ribs 25 are formed. The effect of this disposition of the cams will prevent them from obstructing the functions of each other—that is to 10 say, when the ribs 26 are moving over the tailpieces and forcing the same toward each other the ribs 25, coacting with the jaws proper, will be moving away from said jaw enlargements 18 to permit the operative ends 15 of the jaws to open without interference. In this manner the jaws will not only be positively moved to their clamping and releasing positions, but are retained with certainty in any intermediate position, as it will be evident 20 that no matter what relation they may assume their movement in either direction is absolutely dependent upon the rotary movement of the shell. The particular relation of the several cam-ribs is possessed of still further utility. For instance, they serve as 25 stops for limiting the movement of the sleeve or shell in either direction. This will be made plain by reference to Figs. 6 and 7 of the drawings, wherein it will be seen that rotary movement of the shell in one direction—to wit, that direction in which the jaws will be expanded—will cause the enlargements 18 to abut against the rear ends of the ribs 25 to limit the movement of the shell in one direction, 30 while in like manner the tailpieces will limit the movement of the shell in the opposite direction by abutting against the rear ends of the ribs 26 when the jaws are at the limit of their inward movement.

40 As already stated, the shell or sleeve 24 abuts against the flanges 20 and outstanding portions 19, being thus held against displacement in one direction. It is held against movement in the opposite direction by a 45 holding-nut 27, threaded on a reduced rear portion 28 of the head and having its inner end fitted within the shell. This nut is provided with an annular flange 29, which abuts against the rear end of the sleeve or shell.

50 The nut is held against rotation by a suitable set-screw 30, threaded through the same and bearing against the head. This nut, besides holding the actuating sleeve or shell in place, constitutes a friction-brake to prevent the 55 too free movement of the same and also to take up all looseness or wear.

The manner of manipulating the holder is as follows: When the sleeve is rotated in one direction, the cams bearing against the tailpieces will force the operative ends of the jaws apart to permit the introduction of the tool to be held. After such introduction the sleeve is revolved in an opposite direction, thus throwing the cams 25 into operation

against the enlargements 18, consequently 65 forcing the jaws into engagement with the tool. Another reversal will of course release the tool. For the reasons already given said tool will be held firmly by the structure, and in order that no accidental 70 movement may take place on the part of the sleeve the holding-nut may be screwed into as tight engagement with the same as desired. The holder, moreover, can be manufactured at small cost, as the elements are 75 simple and can be easily assembled. There are no intricate parts liable to derangement or damage and no springs employed in connection with the holding-jaws.

From the foregoing it is thought that the 80 construction, operation, and many advantages of the herein-described invention will be apparent to those skilled in the art without further description, and it will be understood that various changes in the size, shape, 85 proportion, and minor details of construction may be resorted to without departing from the spirit or sacrificing any of the advantages of the invention.

Having thus described my invention, what 90 I claim as new, and desire to secure by Letters Patent, is—

1. A tool-holder, including a head, a pivotally-mounted jaw carried by the head, and a rotary jaw-actuating member mounted on 95 the head and retained against longitudinal movement thereon, said member engaging the jaw on opposite sides of its pivot for swinging the same in opposite directions.

2. A tool-holder, including a head, a pivotally-mounted jaw carried thereby, and a rotary jaw-actuating member mounted on the head and retained against longitudinal movement thereon, said member having inwardly-extending cams that engage the jaw 105 on opposite sides of its pivot for swinging said jaw in opposite directions.

3. A tool-holder comprising a head, a plurality of pivotally-mounted jaws carried thereby, a rotary jaw-actuating member retained against relative longitudinal movement with respect to the head, and means engaging the jaws at opposite sides of their pivots for actuating the jaws through the rotary movement of said member. 110

4. In a tool-holder, the combination with a head and a plurality of pivotally-mounted jaws, of a relatively rotary jaw-actuating member provided with oppositely-disposed offset cams projecting laterally from the actuating member and arranged for engagement with the jaws at opposite sides of the pivots thereof. 120

5. In a tool-holder, the combination with a head and a pivotally-mounted jaw, of a 125 relatively rotary jaw-actuating member provided with offset oppositely-disposed cams projecting laterally from the actuating mem-

ber and arranged to alternately engage with the jaw for swinging the same in opposite directions.

6. In a tool-holder, the combination with a head and a plurality of pivotally-mounted jaws, of a relatively rotary jaw-actuating member retained against relative longitudinal movement with respect to the head and provided with oppositely-disposed cams arranged for engagement with the jaws at opposite sides of the pivots thereof.

7. A tool-holder comprising a head, a plurality of pivotal jaws carried thereby and provided with tailpieces, and a rotary jaw-actuating member having oppositely-disposed cams opposite to the jaws and tailpieces respectively, said cams being arranged out of alignment respecting the longitudinal direction of the holder whereby the rotary movement in opposite directions of the jaw-actuating member serves to positively operate the jaws and is limited by the contact of either of the jaws or tailpieces with the rear ends of the cams.

25 8. A tool-holder comprising a head provided with a plurality of pivoted jaws, and a rotary jaw-actuating member, having means engaging the jaws at opposite sides of their pivots for actuating said jaws through the rotary movement of the jaw-actuating member, said means also constituting a stop for limiting the relative movement of said member in both directions.

9. A tool-holder comprising a head, a plurality of pivoted jaws provided with tailpieces, a sleeve surrounding the head and having internal transversely-disposed cam-shaped ribs arranged to respectively engage the jaws and tailpieces, said ribs having their faces inclined in opposite directions and the ribs coacting with the tailpieces and jaws being disposed in alternate arrangement to effect the positive actuation of the jaws in opposite directions and limiting the movement of the sleeve by the abutting of the rear ends of one set of ribs against the tailpieces, or by the abutting of the other set of ribs against the jaws proper.

45 10. A tool-holder comprising a head, a

plurality of pivotally-mounted jaws carried thereby, a jaw-actuating member mounted on the head and engaging the jaws at opposite sides of their pivots to cause said jaws to approach or recede as the jaw-actuating member is rotated in opposite directions, means for preventing the longitudinal movement of the member with respect to the head, and means for limiting the rotary movement of said member in opposite directions.

50 11. In a tool-holder, the combination with a head, of a jaw movably mounted on the head, a rotatable actuating member for moving the jaw, said member having frictional engagement at one end with the head, and means adjustably mounted on the head and engaging the other end of the actuating member for holding said actuating member in such frictional engagement.

55 12. In a tool-holder, the combination with a head, of a jaw movably mounted on the head, a rotatable actuating member for moving the head, and a nut bearing against one end of the member to hold the same against displacement and to apply friction to said member.

60 13. In a tool-holder, the combination with a head, of a plurality of jaws pivotally mounted on the head, a sleeve rotatably mounted on the head and engaging the jaws to move the same, and a nut screwed on the head and bearing against one end of the sleeve.

65 14. In a tool-holder, the combination with a head having an outstanding flange at one end, a plurality of jaws pivotally mounted on the head, a sleeve revolvably mounted on the head and having one end bearing against the flange thereof, said sleeve engaging the jaws to move the same, and a nut threaded on the head and bearing against the opposite end of the sleeve.

70 In testimony that I claim the foregoing as my own I have hereto affixed my signature in the presence of two witnesses.

MELVIN BARBER.
